UNITED STATES PATENT OFFICE.

NATHANIEL COLE, OF OTTAWA, ILLINOIS.

DESIGN FOR A SINGLE HARNESS-LOOP.

SPECIFICATION forming part of Design No. 34,801, dated July 16, 1901.

Application filed January 18, 1901. Serial No. 43,815. Term of patent 7 years.

To all whom it may concern:

Be it known that I, NATHANIEL COLE, a citizen of the United States, residing at Ottawa, in the county of Lasalle and State of Illinois, have invented and produced a new and original Design for a Single Harness-Loop; and I do hereby declare the following to be a full, clear, and exact description of the same, reference being had to the accompanying drawings, forming a part thereof.

In the said drawings, Figure 1 is an end elevation. Fig. 2 is a plan view, and Fig. 3 is a perspective view, of a single harness-loop embodying my new design.

My design relates to the new and original shape or configuration of the article.

The leading or essential feature consists in the unitary design for a single harness-loop made the subject of illustration, comprising the shape of the top and bottom pieces A B and side pieces C D, formed continuously, so as to constitute a flattened open tube, with square edges at each end, the inner surfaces of the parts A B C D meeting squarely,

so as to form an inner oblong opening of 25 greater length than width or height, and the walls of which opening being rectangular, while the outer surfaces of said united parts A B C D are sharply beveled longitudinally, as shown at *a b c d*, together with the shape 30 of the internal pin E, the same being in the form of a flat-topped frustum of a cone, and rising from the center of the inner surface of the bottom part B and extending to half the height of the space between the solid flat top 35 and bottom pieces A and B.

Having thus described my invention, what I claim as new, and desire to secure by Letters Patent, is—

The design for a single harness-loop, substantially as herein shown and described.

In testimony whereof I affix my signature in presence of two witnesses.

NATHANIEL ^{his} COLE.
